UNITED STATES PATENT OFFICE.

HENRY THOMAS GILL AND HARRY LUCAS, OF BIRMINGHAM, ENGLAND, ASSIGNEES OF
ONE-THIRD TO JOSEPH POTTER, OF EDGBASTON, BIRMINGHAM, ENGLAND.

SAFETY-RAZOR.

1,333,306.

Specification of Letters Patent. Patented Mar. 9, 1920.

Application filed July 8, 1918. Serial No. 243,889.

To all whom it may concern:

Be it known that we, HENRY THOMAS GILL, of 17 Herbert road, Bearwood, Birmingham, in the county of Warwick, England, and HARRY LUCAS, of 57 Sycamore road, Erdington, Birmingham, aforesaid, engineers, have invented Improvements in Safety-Razors; and we do hereby declare the following to be a full, clear, and exact 10 description of the same.

Our invention comprises improvements in safety razors and refers more particularly to that class of such in which a two-edged or a single-edged blade is adapted to be 15 clamped between two members or plates, the edge or edges of one of these plates being of a comb-like form to provide a safety guard. The invention is particularly applicable to the well-known "Gillette" type of razor in 20 which the plates are laterally curved so as to provide a means of adjusting the edges of the blade relatively to the guard; but it may be applied to similar razors of a non-adjustable type.

25 In this class of razor as heretofore made a complete contact between the blade and guard plate prevents the free escape of the hair removed with the result that the razor clogs and becomes inefficient in use.

30 The primary object of the present invention is to overcome this defect and in accordance therewith a series of channels or passages are provided disposed transversely in relation to the guard member. These channels or passages are formed in the guard member or in the blade or in both the guard member and the blade.

35 In the accompanying drawings, in which like parts are designated by similar reference characters throughout the several views:

Figure 1 represents a front view in elevation of a safety razor of the "Gillette" type constructed in accordance with our invention.

40 Figs. 2 and 3 are views in perspective of the handle and outer plate member respectively of the razor.

45 Fig. 4 is an inverted view in longitudinal section, Fig. 5 is a plan view looking upward and Fig. 6 a view in perspective of the guard member of the razor.

Fig. 7 is a view in perspective of a razor blade.

50 Referring more particularly to Figs. 1 to

6 of the drawings, *a* is the guard which may be conveniently cast from aluminium or the like, being made of greater thickness than usual, say three sixteenths of an inch thick. The surface which contacts with the blade 60 is provided with a series of parallel grooves *b*, say eleven, which extend right across the laterally curved surface of the guard *a*. These grooves may be conveniently cast on to the guard member. Intermediate between each groove a high or surface portion in the form of a rib *c* is left against which the blade is clamped, leaving channels through which the hair and soap may freely pass when the razor is being used. 70

The outer plate member *d* may be provided with a screwed member *e* and a pair of upstanding pegs *f* which engage with holes *g* in the guard, the screwed member *e* engaging with the handle *h* in well-known 75 manner.

In lieu of channels or grooves in the guard member, or in addition thereto, shallow grooves or channels *i*, see Fig. 7, may be provided in one or both surfaces of the razor 80 blade, such grooves being laterally directed. Ribs *j* are left between the grooves and form the surface which is clamped against the guard, the channels *i* then permitting the hair and soap to move away clear of the cutting edge of the razor. The usual holes *k* are provided in the blade for positioning and securing the same. 85

What we claim is:

1. In a safety razor, a blade with two 90 oppositely disposed cutting edges, a guard member disposed beneath said blade and having a series of channels extending between and beneath said edges, the tops of said channels being closed by the underside 95 of the blade said channels directly connecting said edges whereby lather removed from the skin by the act of shaving is constrained to pass through said channels to the opposite edge of the blade where it may serve to 100 lather the skin when said opposite edge is employed for shaving and said channels being formed by the spaces between a plurality of ridges upon said guard member, the tops of which ridges being in contact 105 with the blade form supports therefor, said ridges having projecting ends forming teeth at the edges of the guard member.

2. In a safety razor, a blade with two 110 oppositely disposed cutting edges, a guard

member disposed beneath said blade and having a series of channels extending between and beneath said edges, said channels passing continuously from one edge to the other and being formed by the spaces between a plurality of parallel ridges upon and integral with said guard member, said ridges being at right angles to the edges of

the blade the tops of which ridges being in contact with the blade form supports therefor, said ridges having projecting ends forming teeth at the edges of the guard member. 10

In testimony whereof we affix our signatures.

HENRY THOMAS GILL.
HARRY LUCAS.
